CLAIM

The ornamental design for a combined periphery and shoe bottom, as shown and described.

DESCRIPTION

FIG. 1 is a perspective view of the left, front and bottom of a combined periphery and shoe bottom showing my new design, the broken lines partially showing a shoe throughout the views are for illustrative purposes only and form no part of the claimed design;

FIG. 2 is a right side elevational view thereof;

FIG. 3 is a left side elevational view thereof;

FIG. 4 is a bottom plan view thereof;

FIG. 5 is a top plan view thereof;

FIG. 6 is a front elevational view thereof; and,

FIG. 7 is a rear elevational view.
